(57) **CLAIM**

The ornamental design for a signal cable lanyard, as shown and described.

DESCRIPTION

FIG. 1 is a front elevational view of a first embodiment of a signal cable lanyard, the signal cable lanyard including a universal serial bus (USB) plug connected to a USB recep-

tacle, the signal cable lanyard being of indeterminate length, a badge and badge connector being shown in phantom;

FIG. 2 is a left elevational view thereof;

FIG. 3 is a right elevational view thereof;

FIG. 4 is a rear elevational view thereof;

FIG. 5 is a front perspective view thereof, showing the USB plug removed from the USB receptacle;

FIG. 6 is a front elevational view of a second embodiment of a signal cable lanyard, similar to the first embodiment, with the USB plug and the USB receptacle being transposed;

FIG. 7 is a left elevational view thereof;

FIG. 8 is a right elevational view thereof;

FIG. 9 is a rear elevational view thereof;

FIG. 10 is a front perspective view thereof, showing the USB plug removed from the USB receptacle;

FIG. 11 is a front elevational view of a third embodiment of a signal cable lanyard, the signal cable lanyard including a 30-pin plug connected to a 30-pin receptacle, the signal cable lanyard being of indeterminate length, a badge and badge connector being shown in phantom;

FIG. 12 is a left elevational view thereof;

FIG. 13 is a right elevational view thereof;

FIG. 14 is a rear elevational view thereof;

FIG. 15 is front perspective view thereof, showing the 30-pin cable plug removed from the 30-pin receptacle;

FIG. 16 is a front elevational view of a fourth embodiment of a signal cable lanyard, similar to the third embodiment, with the 30-pin plug and the 30-pin receptacle being transposed;

FIG. 17 is a left elevational view thereof;

FIG. 18 is a right elevational view thereof;

FIG. 19 is a rear elevational view thereof; and,

FIG. 20 is a front perspective view thereof, showing the 30-pin plug removed from the 30-pin receptacle.

The broken lines in the figures illustrate unclaimed environment only and form no part of the claimed design.

The signal cable lanyard is shown with a symbolic break in its length. The appearance of any portion of the article between the break lines or beyond forms no part of the claimed design.
